CASTING METHOD AND APPARATUS.

Application filed November 12, 1924. Serial No. 749,476.

This invention relates to the art of casting metals, especially ferrous metals, as iron and even steel; the invention being highly advantageous even in the art of casting by 5 the rotary or so-called centrifugal method.

The present invention has also as an object, in the latter connection, to provide an improved method, and apparatus for facilitating said method and to render the latter 10 particularly valuable for the making of cast iron pipe or other elongated generally cylindrical articles in permanent or rotary molds of metal,—although of course the invention is seen to be of value in rotary 15 casting whatever be the material or character of the mold and whatever the nature and shape of the cast article.

The prime object of the invention is to provide a method of supervising the ultimate qualities of the cast articles, and a method characterized by the employment of a vaporous medium in heat-transfer relation to the mold during the pouring of the charge and its cooling to form a casting, 25 and also preferably, during extraction of the casting and during the period starting with such extraction and ending with the pouring of a second charge. A vaporous medium has been heretofore proposed in this art, to wit, an aqueous vapor (steam). But steam has a comparatively low vaporization temperature; and it has been ascertained that to employ steam at high enough 30 temperatures to heat the mold to the minimum temperature required to defeat too rapid congelation and cooling of the charge, and incidentally too great changes of temperature of the mold, the pressures at which the steam must be at times maintained are so high as not to permit an economical and 35 practical structural design for the mold and particularly for the steam chamber associated therewith. It has been calculated that, where steam is used, the confining walls for holding the steam, and the joints between such walls, must be capable at times of 40 withstanding a pressure of approximately 2,000 pounds per square inch.

According to the present invention, however, the object thereof being here considered is perfectly attained by the use of a non-aqueous vapor, and preferably, by the use of a metallic vapor, which may be maintained at a very high temperature but at a comparatively low pressure, due to the

solid or liquid from which the vapor is generated having a vaporization temperature very much higher than that of water. As the problem faced is now understood, the metallic vapor to be employed is mercury 60 vapor, diphenyl oxide or some other material capable of passing into the vaporous state at high temperatures and low pressures as compared to steam.

Further, the invention is adapted to attain various other objects, which will be clearly understood from the hereinbelow disclosure of a preferred method of carrying out the invention. Some of such objects may be briefly mentioned, as follows: 65

Another object is to provide an exceedingly simple casting machine, and one particularly wherein the mold even if a rotary one, will be rugged and long lived; and a machine adapted to be easily subjected to 70 the vaporous medium proposed by the present invention.

Another object is to provide a casting machine wherein the congelation and cooling of the casting may be supervised by the use 80 of a vaporous medium which may be increased or decreased in quantity by movements of portions of the vapor toward and away from the mold, that is, into and out of the machine, by way of a single combined 85 inlet and outlet; whereby in operation such inlet and outlet may be of small diameter compared with the mold.

Another object is to provide a rotary casting machine with said inlet and outlet arranged concentric with the axis of rotation of the mold, thus in turn to avoid swinging or gyrating connections and at the same time make perfectly practical the use of the well-known labyrinth or other suitable packing to 90 provide an absolutely vapor-tight joint, between two relatively movable members for forming conduit means for the vapor. 95

Another object is to provide a method of operating a plurality of casting machines 100 while supervising the ultimate qualities of the castings made in them, by the use of quantities of the vapor medium in such a way as to permit the heat absorbed by portions of the medium bled at the proper instant from one machine, to be added at the proper instant to the heat content of the portion of the medium in heat-transfer relation to another of the casting machines. 105

Another object is to provide a circulatory 110

system, such system including vapor chambers in a plurality of the casting machines, and a vaporization chamber exterior to said machines for holding a collection of vapor generating material, as liquid mercury, associated with various by-pass conduits and separately operable valves in various parts of the system; whereby the vapor may be, at will, led into and out of the vapor chambers in the casting machines, or whereby the vapor pressure in each of said chambers may be maintained or modified, and whereby at the same time large quantities of liquid mercury may never accumulate in any of said chambers, and the vapor and liquid may be maintained always sealed in and at least to some extent circulating through the system.

The invention will be more clearly understood from the following description, when taken in connection with the accompanying drawing, showing one apparatus adapted to constitute an embodiment, but an illustrative one only, of a casting machine, of a collection of such machines, and of the system aforesaid, all facilitative of a carrying out of the method of the invention.

In the drawing,

Fig. 1 shows more or less diagrammatically, the system just mentioned including a battery of three casting machines; and

Fig. 2 is a horizontal axial sectional view of one of such machines.

Referring first to Fig. 2, which is also somewhat diagrammatic in that the anti-friction journalling means for the outer casing is merely indicated at 3, such machine includes a metal mold 4, an outer casing 5, an end plate 6 for the mold, a spider 7, a cone-casing 8 and a packing-cover 9, all of which rotate as one unit, relative to a fixed conduit 10 and the latter's packing cover 11.

Said covers 9 and 11 house a labyrinth or other suitable type of packing, thus making a vapor-tight joint between members 8 and 10 during rotation of the mold and its associated parts as thus described. Thus, since also cone-casing 8 and outer casing 5 are welded as indicated at 12, outer casing 5 and mold 4 are welded as indicated at 13, and mold 4 and plate 6 are welded as indicated at 14, there are provided at all times, and whether the mold is rotating or not, a vapor chamber 15 sleeving the mold, a vapor vestibule 16 always in communication with conduit 10, and means for maintaining the vestibule always in open communication with chamber 15, to wit, the ports 17 in spider 7.

This spider also has a central opening which snugly accommodates a cylindrical projection 18 offset from the center of closing plate 6. Thus the spider is itself held in place by its illustrated engagements with casing 5 and plate 6, in turn supports said plate co-axial with the mold, and adapts

the plate to support the inner end of the mold.

Referring now to Fig. 1, the three casting machines are seen at A, B and C. The outer casings of these machines are shown at 5^a, 5^b and 5^c, the cone-casings at 8^a, 8^b and 8^c and the fixed conduits joined to the cone-casings, by the labyrinth or similar packing, at 10^a, 10^b and 10^c.

Each of these conduits leads from a vapor conduit or manifold 19 one end of which opens into the upper portion of a liquid mercury boiler 20 and the other end of which opens into the condensing chamber of a condenser 21. The liquid levels in the devices 20 and 21 are indicated at 22 and 23. The boiler 20 may be heated in any suitable way, as by passing heated vapors, say from the stack of the cupola delivering the molten metal, through a duct 24. Such vapor as is condensed in condenser 21 passes from the condenser to the boiler, by way of conduits 24^a, 25 and 26, a pump 27 being interposed in conduit 24 to maintain circulation. The condenser includes suitable cooling coils or other passages forming parts of an auxiliary circulatory system for water and steam, such system including a water inlet conduit 28 and a stem outlet conduit 29.

Conduits 10^a, 10^b and 10^c have branch conduits 30^a, 30^b and 30^c, all leading to a conduit or manifold 31 leading to a suitable condensing chamber in an auxiliary condenser 32 similar to condenser 21 especially in that condenser 32 has associated with it a water inlet conduit 33 and a steam outlet conduit 34 exactly as the conduits 28 and 29 are associated with the condenser 21. The mercury chamber or condenser 32 discharges into a conduit 35 leading to a pump 36. This pump discharges into a conduit 37, leading, as does conduit 25 from pump 27, to the return conduit 26 going back to the boiler 20.

In each of conduits 10^a, 10^b and 10^c, is a separately operable valve 38, and in each of the conduits 30^a, 30^b and 30^c, is a separately operable valve 83.

Operation: Assuming the system cold, and assuming the liquid mercury level is as indicated by the lines 22 and 23, it is first ascertained that the valves 38 in the conduits 10^a, 10^b and 10^c are all open and that the valves 83 in the conduits 30^a, 30^b and 30^c are all closed. Then the heated gases are passed through duct 24 until the mercury liquid in the boiler generates vapor. Such generation is continued until the chambers 15 in all the machines are filled with vapor at the correct pressure to raise the temperature of each mold 4 to that predetermined. Until such a condition is attained, of course, the pump 27 is idle, and no or very little water is being passed through conduit 28 and into the condenser. Also, of course, pump 36 is

idle, and no water is being passed through pipe 33 into condenser 32.

While the metal charge for the first casting is being poured and shaped in the mold of say machine A, the valve 38 of conduit 10^a is wholly closed. As soon as it is required to lower the temperature of the mold of machine A, that is, as soon as the actual creation of the casting is to occur, said valve 10 38 is opened to the required amount and, if necessary, one of both of the valves 38 in conduits 10^b and 10^c are wholly or partially opened. Possibly, if the next casting is to be made say in machine B, the valve 38 15 in conduit 10^b may be wholly opened and the valve 38 in conduit 10^c may be wholly or almost wholly closed. These valve manipulations will be such that the heat units abstracted from the setting metal in one machine will be passed on to the vapor in heat-transfer relation to the mold of the machine to be used for the next casting; and so on. Thus gradually the vapor chambers of all the machines of the battery to be used for any 20 particular run, are filled and held filled with vapor at the proper pressure to take care of the schedule of successive pourings relative to the various machines; permitting a charge in one machine to set and cool at 25 the predetermined rate, and to hold the casting in say still another machine at a temperature such that the casting may be rigid enough to be slid out of the machine and yet not cooled enough to commence to 30 chill as the result of its contact with the metal mold during the process of extraction.

It will thus be understood that during each casting operation in any of the machines, it is required at times, not only to raise the temperature of the mold, but to reduce such temperature, and to make this reduction at a certain predetermined rate. The temperature of a mold is always increased really by increasing the pressure 40 of the vapor blanket for that mold, and decreased by decreasing the pressure of such blanket. Thus it is that the single conduit 10^a, 10^b or 10^c serves to modify the vapor blanket of the associated machine, 45 quantitatively as well as qualitatively. Also at times, obviously, the pressure and content of a particular vapor blanket, must be reduced without affecting the similar characteristics of another blanket or the other blankets; and this is why the auxiliary conduits 30^a, 30^b, and 30^c, and their valves 83, are provided. Whenever the pressure or content of a vapor blanket of one 50 of the machines is to be reduced, but without causing a variation in the vapor pressure in conduit 19, the valve 83 interposed in the appropriate conduit 30^a, 30^b or 30^c is partially or wholly opened, but first the valve 38 in the associated conduit 10^a, 10^b or 10^c is 55 fully closed. It will be understood that the

manipulations of the various valves 38 and 83 will in practice depend on many factors and particular exigencies, and a description of all possible operations of such valve settings would make the specification too 60 extended.

Water is of course passed through pipes 28 and 33 and into condensers 21 and 32 as the accumulations of vapor at too high temperatures occur in different parts of the 65 system. It has been carefully calculated that after the making of several castings in one or more of the machines, the pressure of the vapor in the system will rise so high that uninterruptedly thereafter and during 70 continuance of the run, heat units will have to be absorbed from the vapor by way of the condensers,—thus serving the useful purpose of delivering steam in large quantities through the conduits 29 and 34, for 75 doing work about the foundry, in operating the machines and otherwise.

The system may obviously be operated as above described, even when the boiler 20 is not used at all as a generator of the heat 80 to be stored in the vapor blankets in the casting machines. Thus, such boiler may be used solely as a balancer element for the system, exactly as a fly wheel is used on an engine shaft receiving rotation-impulses 85 intermittently. In such case, it has been calculated that only the first two or three pipes made will be chilled, or at worst have to be scrapped and remelted. According to this 90 method of operation, only enough heat will 95 be initially given by way of the boiler 20 to fill the system and particularly the vapor chambers of all or some of the machines with vapor, at a low enough temperature not sufficient materially to raise the temperature 100 of the molds. Each vapor blanket, and also all the vapor in the system, would very shortly become charged with so much heat from the first two or three castings congealing that the main problem thereafter 105 would be to cause, as above described, transferences of some of this heat from different parts of the system to other parts thereof, while utilizing the surplus heat to generate 110 steam in the conduits 29 and 34; the boiler 115 20, being run at a very low temperature, continuously or sporadically, in order merely to act as a balancer as aforesaid to compensate for intermittent pressure drops in the conduit 19, and then only, in all probability, when castings are not made at the predetermined intervals, due say, to an unexpected wait for more molten metal.

I claim:

1. In the art of rotary casting of metals, 125 the method of varying the temperature of the mold by the variation of the pressure of a vapor in heat exchanging relation with the mold.
2. In the art of rotary casting, the method 130

- of controlling the rate of heat-conduction from the molten metal pour through the mold, which involves rotating the mold while maintaining the mold in heat-transfer relation to a collection of vapor and varying the pressure of such vapor during the forming and cooling in the mold of the casting being formed in said mold from the molten metal.
3. The method as claimed in claim 1 characterized by the fact that the vapor is maintainable at a lower pressure than superheated steam at the same temperature.
4. The method as claimed in claim 1 characterized by the fact that the vapor is non-aqueous vapor.
5. The method as claimed in claim 1 characterized by the fact that the vapor is a metallic vapor.
6. The method as claimed in claim 1 characterized by the fact that the vapor is mercury vapor.
7. The method as claimed in claim 1 characterized by the fact that the vapor is generated from a liquid having a vaporizable temperature higher than water.
8. In the art of rotary casting, the method of supervising the ultimate qualities of the articles cast, which involves providing a mold including metallic portions forming parts of the mold cavity, rotating said mold, and while holding a molten charge in the mold maintaining said portions of the mold in heat-transfer relation to a collection of vapor and modifying the pressure of such vapor.
9. In the art of rotary casting, the method of supervising the ultimate qualities of the articles cast, which involves providing a mold including metallic portions forming parts of the mold cavity, rotating said mold, and, between the introduction of a molten charge in the mold to make a first casting, and the introduction of another charge to make a second casting following extraction of the first casting, maintaining said portions of the mold in heat-transfer relation to a collection of vapor and modifying the pressure of such vapor.
10. In the art of rotary casting, the method of supervising the ultimate qualities of the articles cast, which involves utilizing a mold including metallic portions forming parts of the mold cavity, and during the making of several successive castings, maintaining said portions of the mold in heat-transfer relation to a collection of non-aqueous vapor and modifying the pressure of such vapor during each casting operation and between successive casting operations.
11. In the art of rotary casting, the method of operating a plurality of molds to supervise the ultimate qualities of the articles cast by said molds, which involves maintaining separate collections of vapor in heat-transfer relation to each of said molds, at intervals bleeding vapor from one of such collections, at intervals adding vapor to one of such collections, providing a circulatory system for the vapor thus bled and the vapor thus added, and confining all the vapor employed in connection with said plurality of molds in said system.
12. The method defined in claim 11, where-
in said vapor is non-aqueous.
13. The method defined in claim 11, where-
in said vapor is non-aqueous, and wherein surplus heat units in the non-aqueous vapor in said system are used to generate aqueous vapor.
14. In the art of casting, the method of controlling the rate of heat-conduction from the molten metal pour through the mold, which involves confining a vapor for travel toward and away from heat-transferring relation to the mold, and predeterminedly affecting said travel of the vapor to control the rate of cooling of the pour.
15. In the art of casting, the method of controlling the rate of heat-conduction from the molten metal pour through various molds, which involves confining a vapor for heat-transfer relation to a plurality of said molds simultaneously.
16. In the art of casting, the method of controlling the rate of heat-conduction from the molten metal pour through various molds, which involves confining a vapor for heat-transfer relation to a plurality of said molds simultaneously, and maintaining collections of such vapor in heat-transfer relation to different molds, at different temperatures.
17. In the art of casting, the method of controlling the rate of heat-conduction from the molten metal pour through the mold, which involves subjecting such mold to heat-transfer relation to a collection of vapor, and modifying the pressure of said vapor by modifying the spatial characteristics of the collection.
18. In the art of casting, the method of controlling the rate of heat-conduction from the molten metal pour through the mold, which involves confining a vapor for travel toward and away from heat-transfer relation to the mold, and controlling such vapor travel to affect the rate of cooling of the pour.
19. In the art of casting, the method of controlling the rate of heat-conduction from the molten metal pour through the mold, which involves confining a vapor for travel toward and away from heat-transfer relation to the mold, and predeterminedly affecting said travel of the vapor to control the rate of cooling of the pour, said vapor being maintainable at a high temperature and a low pressure as compared to steam.

20. In the art of casting, the method of controlling the rate of heat-conduction from the molten metal pour through the mold, which involves subjecting such mold to heat-transfer relation to a collection of vapor, and modifying the pressure of said vapor by modifying the spatial characteristics of the collection, said vapor being a non-aqueous vapor.
- 10 21. In the art of casting, the method of controlling the rate of heat-conduction from the molten metal pour through the mold, which involves confining a vapor for travel toward and away from heat-transfer relation to the mold, and controlling such vapor travel to affect the rate of cooling of the pour, said vapor being a metallic vapor.
22. In the art of casting, the method of controlling the rate of heat-conduction from the molten metal pour through the mold, which involves subjecting such mold to heat-transfer relation to a collection of mercury vapor.
- 25 23. In the art of casting, the method of controlling the rate of heat-conduction from the molten metal pour through the mold, which involves subjecting such mold to heat-transfer relation to a non-oleaginous vapor generated from a liquid having a vaporization temperature considerably higher than water and considerably lower than zinc.
- 30 24. In the art of casting, the method of controlling the rate of heat conduction from the molten metal pour through the mold, which involves subjecting such mold to heat-transfer relation to a collection of vapor, and modifying the temperature of said vapor by modifying the natural ability of the same to vary its pressure.
- 35 25. In the art of casting, the method of controlling the rate of heat conduction from the molten metal pour through the mold, which involves subjecting such mold to heat-transfer relation to a collection of vapor, and modifying its degree of confinement in the vicinity of the mold as compared with its degree of confinement at a point comparatively remote from the mold.
- 40 26. In the art of casting, the method of controlling the rate of heat-conduction from the molten metal pour through the mold, which involves subjecting such mold to heat-transfer relation to a collection of vapor, and modifying the pressure of said vapor by modifying the spatial characteristics of the collection, said vapor being maintainable at a high pressure and low temperature as compared to steam.
- 45 27. In the art of casting, the method of controlling the rate of heat-conduction from the molten metal pour through the mold, which involves maintaining the mold in heat-transfer relation to a collection of metallic vapor.

R. BURDETTE DALE.
